UNITED STATES PATENT OFFICE.

JOHN D. TAYLOR, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-SIGNAL.

1,170,361.

Specification of Letters Patent.

Patented Feb. 1, 1916.

Application filed August 28, 1912, Serial No. 717,436. Renewed November 12, 1915. Serial No. 61,158.

To all whom it may concern:

Be it known that I, JOHN D. TAYLOR, a citizen of the United States, residing at Edgewood Borough, in the county of Allegheny and State of Pennsylvania, have invented certain new and useful Improvements in Railway-Signals, of which the following is a specification.

My invention relates to railway signals of 10 that type comprising a signal device in the form of a semaphore biased to one position of indication, and an electric motor for moving it to one or more other positions of indication.

15 I will describe one form of railway signal embodying my invention, and will then point out the novel features thereof in claims.

In the accompanying drawings, Figure 20 1 is a view showing in side elevation, partly sectioned, one form of signal embodying my invention, the semaphore being removed. Fig. 2 is a view showing on an enlarged scale a portion of the signal shown in Fig. 25 1. Fig. 3 is an end view of the apparatus shown in Fig. 2 with the end plate removed. Fig. 4 is a view on the line IV—IV of Fig. 2 looking in the direction of the arrow. Fig. 5 is a bottom view of a portion of Fig. 4. Fig. 6 is a diagrammatic view showing one arrangement of winding for the motor employed to move the signal device. Fig. 7 is a view showing in front elevation the signal shown in Fig. 1 and including the semaphore. Fig. 8 is a diagrammatic view showing one arrangement of circuit and apparatus when the signal shown in the preceding views is employed as a three-position signal. Fig. 9 is a diagrammatic view showing one arrangement of apparatus and circuits when the signal shown in Figs. 1 to 7 is employed as a two-position signal. Fig. 10 is a view showing a modified form of part of the apparatus 40 45 shown in Figs. 1, 2 and 3.

Similar reference characters refer to similar parts in each of the several views.

Referring first to Figs. 1 and 7, 27 is an outside signal case (only the front portion 50 of which is shown in Fig. 1) within which is mounted a gear-inclosing casing 13. The casing 13 is fixed to the front of case 12 by bolts 13^a. Mounted in bearings in casing 13 is a shaft 10 one end of which pro-

jects through a hole 4 in case 27 and to the 55 projecting end of which a semaphore 100 may be fixed. The semaphore is shown in Fig. 7 but not in Fig. 1. The semaphore is biased by gravity to a horizontal position, usually termed the danger position, 60 and is moved to one or more other positions, such as to a caution and a clear position, by means hereinafter explained. In the signal here shown the semaphore is moved upwardly to its other positions of indication, but it is understood that the mechanism may equally well be arranged for the semaphore to be moved downwardly from its horizontal position to its other positions of indication. 70

Fixed to the casing 13 is a cylindrical box 37 in which is journaled a spindle 15. This spindle is operatively connected with the semaphore shaft 10 by suitable gearing comprising a segmental gear wheel 26 fixed on 75 shaft 10, a pinion 24 and a gear wheel 23 both fixed on a shaft 25 journaled in casing 13, a pinion 22 and a gear wheel 21 rigidly connected and mounted on ball bearings carried on shaft 10, and a pinion 17 mounted 80 on the spindle 15. The pinion 17 is not fixed on spindle 15, but is connected therewith in the following manner: As shown clearly in Fig. 2, the pinion 17 is provided with a conical bore which fits upon a conical sleeve 18 secured to the spindle 15. The pinion is held with pressure against the conical sleeve by means of a spring 19 one end of which abut against a collar 20 which abuts against the pinion, and the 90 other end of which spring rests against a shoulder 101 fixed to an extension 15^a on the spindle 15. The friction between the pinion 17 and the conical sleeve 18, due to the compression of spring 19, is sufficient 95 to hold the two in engagement under ordinary conditions, but is such as to permit slippage between the two in case the semaphore falls against its stop with a blow.

Mounted in box 37 is an electric motor M 100 which is employed to move the semaphore 100 from its horizontal position to its other positions of indication. This motor, as here shown, is of the induction type comprising a stator 36 and a squirrel-cage rotor 11. The 105 rotor 11 is carried by a spider 16 (see Fig. 3) which is freely mounted on the spindle 15 and is operatively connected therewith

by means of a ratchet device R. This ratchet device is so arranged that the motor is connected with the spindle 15 when it is to move the semaphore, but that the motor 5 may rotate backward without rotating the spindle 15. It will be seen that by means of this ratchet device, the rotor 11 is rotated backwardly while the semaphore 100 is returning toward its horizontal position, but 10 that when the semaphore is stopped during this movement the rotor 11 is left free to spin idly until its momentum is absorbed, thereby avoiding injury due to sudden stoppage. Also, it will be seen that by causing 15 the rotor to rotate backwardly during movement of the semaphore toward horizontal position, the motor may, if desired, be employed to check the momentum of the moving parts as the semaphore approaches a position at which it is to be stopped. One arrangement of winding of the stator 36 is 20 shown diagrammatically in Fig. 6. As here shown, the stator is provided with two phase windings 54 and 55, which windings 25 are distributed in a manner similar to that shown, so that, while the semaphore is moving toward danger, if alternating current of the same phase is supplied to both windings, or if alternating current is supplied to one 30 winding only and the other winding is closed on itself, the motor acts as a brake to retard the movement of the parts.

As here shown, the ratchet device R comprises a ratchet wheel 32 secured to the 35 spindle 15, and two pawls 33 freely pivoted at points 35 on an arm 14 which is freely mounted on the spindle 15. The pawls 33 are engaged by studs 34 mounted in spokes of the spider 16. The arm 14 is held in frictional engagement with the ratchet wheel 32 by a spring 102. When the spider 16 turns in the direction of the arrow in Fig. 3, that is, when the motor is to move the semaphore, the friction of the arm 14 on the ratchet 45 wheel causes this arm to turn the pawls 33 on their pivots so as to engage the teeth of the ratchet wheel. When however the spider 16 turns in the other direction the pawls are turned by the arm 14 out of the path of the 50 teeth on the ratchet wheel. The ratchet is therefore noiseless when inoperative, and is therefore free from unnecessary wear, and it engages with certainty when operative. Located also in the box 37 is a holding device 55 H adapted to hold the semaphore 100 in caution and clear positions. This device comprises a stator or primary member 29, and a rotor or secondary member 48. It will be seen, therefore, that this holding device 60 is a transformer device having a fixed primary member 29 and a movable secondary member 48. The stator 29 is fixed in the box 37 and comprises a plurality of laminations of transformer iron clamped 65 together by rivets. The rotor is carried

by a spider 12 which as here shown is freely mounted on the spindle 15. Interposed between the rotor 48 and the spindle 15 is a ratchet device R' which is similar to the ratchet device R hereinbefore explained. 70 The ratchet device R' operates to engage the rotor 48 with the spindle when the semaphore moves or tends to move toward danger position, but permits movement of the spindle 15 in the other direction without 75 engaging the rotor 48. As shown in Figs. 1 and 2, the spider 12 is retained in position on the spindle 15 by the ratchet device R' and by a collar 112 fixed to the spindle 15 by a pin 113. It is understood however that 80 in some cases the rotor 48 may be rigidly secured to the spindle 15 as indicated in Fig. 10. The stator 29 comprises a plurality of inwardly projecting pole pieces 50 (as here shown, eight in number). Each pole piece is 85 provided with a coil 31 the coils being so wound that the polarity of the pole pieces is alternately north and south around the stator. The rotor 48 comprises soft iron laminations having embedded therein a plurality of rods 52 equal in number to the number of stator pole pieces. These rods 52 may be of any suitable electro-conductive material such as copper. The rods 52 are connected together by means of copper rings 30 90 at the ends of the rotor. At such times as the holding device H is to hold the semaphore, the coils 31 are energized from a suitable source of alternating current.

The action of the holding device in holding the signal is due to the fact that the magnetic flux from the poles 50 tends to hold the rods 52 in the middle of the field of flux, because this is the position in which no current will be induced in the rods. Considerable force is required to move the rods from this middle position and this force increases rapidly as the rods approach the edges of the poles.

The holding device H as here shown is 110 arranged to control a circuit controller. For this purpose a slot 51 is cut through the stator laminations, and the gap in the magnetic circuit thus formed is bridged by a movable armature 46. To cause part of the 115 flux from the adjacent poles to pass through this armature instead of returning around the stator, a low resistance circuit is placed on the adjacent poles 50. Each of these circuits comprises two copper rods 53 electrically connected at each end of the stator by means of copper plates 49. This low resistance circuit is so placed that its plane is parallel to the normal direction of the flux. The low resistance circuits formed by the 120 rods 53 and plates 49 do not interfere in any way with the flux which passes through the rotor 48, but they compel part of this flux to return by way of the movable armature 46, which flux causes the armature to be 125 130

lifted toward the stator 49. This action of these low resistance circuits is due to the fact that the flux in the halves of the poles nearest the gap would, if it were to return 5 through the unbroken part of the stator, be compelled to pass through the corresponding low resistance circuit, but this circuit offers considerable impedance to such flux so the flux, or a portion of it passes through 10 the branch circuit including the armature 46. The armature 46 is composed of soft iron and is preferably made up of laminations held together by a clamp 44, which clamp is riveted to a pivotally mounted lever 15 45. The laminations of armature 46 are parallel with the paper in Fig. 4, hence they are not shown in the drawings. Two contact fingers 40 and 41 are mounted on the lever 45 by means of insulating studs 47. 20 One of these fingers 40 is arranged to engage with a contact block 42 when the armature is picked up and the other finger 41 is arranged to engage with a back contact 43 when the armature is down. 25 Referring now to Fig. 8 I will explain one form of signaling system employing three-position signals embodying my invention, that is, signals each of which is adapted to indicate danger, caution and clear. In this 30 view A, B, C and D are four successive blocks of a railway over which traffic moves in the direction indicated by the arrow. Signal S governs traffic through block A, signal S¹ governs traffic through block B, 35 and signal S² governs traffic through block C. Each signal is controlled by a relay R, R¹ or R², each of which relays as here shown comprises two windings 104 and 105 one of which, 105, is connected with the track rails 40 and the other of which, 104, is energized from the secondary 107 of a transformer T, T¹ or T², the primary windings of which 45 transformers are energized from signal mains 103. These signal mains are supplied with alternating current from a suitable 50 source, which source is not here shown. Another secondary 108 of each transformer T, T¹ and T² is connected with the rails of the preceding block through a pole-changer 109 55 operated by the adjacent signal. Each pole-changer 109 may be included in the circuit controller 28 shown in Fig. 1, but is here shown diagrammatically as being of a different form for the sake of clearness. The 60 armature member 105 of each relay operates a contact finger 74 which finger engages with wire 80 when the member 105 is oscillated in one direction, with wire 81 when the member 105 is oscillated in the other 65 direction, and which finger is disconnected from both wires 80 and 81 when the member 105 occupies its middle position, that is, when the relay is deenergized. The motor M and holding device H for each signal are 70 energized from secondary 107 of the ad-

jaacent transformer T, T¹ or T², the circuits for these motors and holding devices being controlled by the relays R, R¹ and R². These circuits are also controlled by segments 72, 59, 64 and 69 which are included 75 in the circuit controller 28 shown in Fig. 1.

The operation of the system shown in Fig. 8 is as follows: As shown in the drawing block A is occupied by a car or train W so that relay R is deenergized and signal S 80 therefore indicates danger. Relay R¹ is energized in one direction so that signal S¹ indicates caution, and R² is energized in the other direction so that signal S² indicates clear. When the car or train W passes out 85 of block A, relay R will be energized in such direction that contact finger 74 connects with wire 80 and a circuit will then be closed as follows—from transformer secondary 107 through wire 79, contact finger 74, 85 wire 80, finger 65, segment 64, finger 66, wire 86, where the current will divide, part of it passing through resistance 57, wire 88, motor winding 54 and wire 91 to secondary 107, and the other part of it passing through 90 reactance 58, wire 89, motor winding 55, wire 91 to secondary 107. This current will operate the motor M to move the signal S toward caution position; when caution position is reached the circuit just traced will be 95 opened at contact 66 and the motor therefore stops. Just as the caution position is reached, however, a circuit will be closed through winding 31 of the holding device H which circuit is as follows—from wire 80 100 through finger 63, segment 59, finger 62, wire 92, winding 31, wire 90 to wire 91. The signal will therefore be held in the caution position and the parts of the mechanism for signal S will then be in the positions in 105 which the parts of the mechanism of signal S¹ are shown in the drawing.

While signal S was moving to the caution position, pole-changer 109 operated by this signal was reversed, thereby reversing the 110 position of relay R¹ so that contact finger 74 of this relay connects with wire 81. This closes the following circuit—from secondary 107 of transformer T¹ through wire 79, contact finger 74, wire 81, finger 67, segment 115 69, finger 68, wires 83 and 86, then as before through resistance 57, reactance 58 and the two motor windings 54 and 55, wire 91 to secondary 107. Current in this circuit operates the motor M to move signal toward 120 clear position; when that position is reached the circuit just traced is opened at contact finger 68 and the motor therefore stops. Just as the signal reaches the clear position a circuit is closed through the winding of 125 the holding device H as follows—from wire 81 through wire 82, contact finger 60, segment 59, contact finger 61, wire 92, winding 31, wire 90 to wire 91. The signal is therefore held in the clear position, and the parts 130

of the mechanism of signal S^1 occupy the positions in which the parts of the mechanism of signal S^2 are shown in the drawing. If, while the signal S^2 is in the clear position, a car or train enters block C, it will de-energize relay R^2 thereby opening the circuit through the holding device H of this signal so that the signal is then free to return under the influence of gravity to the danger position. If, when signal S^2 is in the clear position as shown in the drawing, a car or train enters block B from a siding, the contact finger 74 of relay R^2 will be reversed so that the circuit of the holding device H of signal S^2 is opened. The de-energizing of this holding device releases the signal, and it also allows armature contact finger 41 to drop thereby engaging with its back contact 43. Shortly before the signal reaches caution, contact springs 70 and 71 will be electrically connected by segment 72, thereby closing the following circuit—from secondary 107 of transformer T² through wire 79, contact finger 74, wires 80 and 84, contact finger 43, finger 41, wire 85, contact finger 70, segment 72, contact finger 71, wires 87 and 89, motor winding 55, wire 91 to secondary 107; also a branch of this circuit is closed from wire 87 through reactance 58, resistance 57 and motor winding 54. The reactance and resistance in this circuit being in series practically neutralize each other's effect, so that the current in winding 54 is substantially in phase with the current in winding 55. These currents of the same phase in both windings of the motor cause the motor to act as a brake, thereby retarding the downward movement of the signal to such an extent that the holding device H can easily stop the signal and hold it in the caution position. When the caution position is reached a circuit is closed through the holding device H as hereinbefore traced, thereby energizing this device so that the signal is held in caution position. The energizing of device H also raised contact finger 41 away from its back contact 43, thereby opening the braking circuit so that the motor may then be energized to move the signal to clear position again.

It will be evident that when a signal embodying my invention is employed as shown in Fig. 8, the contact finger 40 and front contact 42 shown in Figs. 4 and 5 are unnecessary and may be omitted. It will also be evident that when the signal is employed in this manner, the holding device H is energized only at such times as it is desired that this device should hold the signal; hence in such cases the ratchet device R¹ may be omitted and the rotor 48 may be fixed to the spindle 15 by a pin 110 as shown in Fig. 10.

In Fig. 9 I have shown one form of rail-way signaling system employing two-posi-

tion signals embodying my invention, that is, signals each of which is adapted to indicate danger and clear. In this view A and B are two successive blocks through which traffic in the direction of the arrow is governed respectively by signals S and S^1 . These signals are controlled respectively by track relays R³ and R⁴. Current is supplied to the track relay R⁴ of block B by a secondary 108 of a transformer T whose primary is energized from signaling mains 103, and it is understood that the track relay R³ of block A is energized in a similar manner.

As shown in the drawing, block A is occupied by a car or train W so that relay R³ is deenergized and signal S is therefore at danger. When this car or train passes out of block A, relay R³ will close thereby closing the following circuit through the winding of holding device H—from secondary 107 of transformer T through wire 79, contact 110, wire 92, winding 31, and wires 90 and 91 to secondary 107. Current in this circuit causes the holding device H to close contact 40 thereby closing the following circuit through the winding of motor M—from transformer secondary 107 through wires 79 and 93, contacts 42 and 40, wire 94, contact finger 65, segment 64, contact finger 66, wire 86 and then through resistance 57 and reactance 58, wires 88 and 89, motor windings 54 and 55, to wire 91 and secondary 107. This current energizes the motor M so that the signal is moved to the clear position. Just as the signal reaches the clear position, the circuit last traced is opened at contact finger 66 so that the motor M then stops. The signal is held in the clear position by the holding device H which continues to be energized. The parts of the mechanism of signal S then occupy the positions in which the parts of the mechanism for signal S^1 are shown in the drawing.

If, with signal S^1 in the position shown in the drawing, a car or train enters block B, it will open relay R⁴ thereby opening the circuit of holding device H so that signal S^1 is free to move to danger position.

It will be evident that when a signal embodying my invention is employed as shown in Fig. 9, the contact finger 41 and back contact block 43 shown in Figs. 4 and 5 are unnecessary and may therefore be omitted.

Although I have herein shown and described only one form of railway signal embodying my invention, it is understood that various changes and modifications may be made therein within the scope of the appended claims without departing from the spirit and scope of my invention.

Having thus described my invention, what I claim is:—

1. In combination, a signal biased to one position of indication, means for moving it

to another position, and a transformer device for holding the signal in the last-mentioned position, said device comprising a primary member and a secondary member 5 one of which is fixed and the other of which is movable.

2. In combination, a signal biased to one position of indication, means for moving it to another position, and a holding device 10 for holding the signal in the last-named position said device comprising a stator provided with an energizing winding and a rotor provided with closed electric circuits.

3. In combination, a signal biased to one 15 position of indication, means for moving it to another position, and an inductive device for holding the signal in the last-named position; said device comprising a stator, a squirrel-cage rotor having the same number 20 of bars as the stator has poles and a single phase winding for the stator.

4. In combination, a signal biased to one 25 position of indication, means for moving it to another position, a holding device for holding the signal in the last-named position, 30 said device comprising a stator having an energizing winding and a rotor having closed electric circuits, and means for operatively connecting said holding device with the signal only when the latter is moving or tending to move toward its biased position.

5. In combination, a signal biased to one 35 position of indication, means for moving it to another position, and a transformer device for holding the signal in the last-mentioned position, said device comprising a fixed primary member and a movable secondary member operatively connected with the sign- 40 al.

6. In combination, a signal biased to danger position, means for moving it to caution and clear positions, and a holding device for holding it in the two last-named positions, 45 said device comprising a stator having an energizing winding and a rotor having closed electric circuits.

7. In combination, a signal biased to one 50 position of indication, means for moving it to another position; and an inductive device for holding the signal in the latter position comprising a stator, a rotor, an energizing winding for the stator, a tractive armature, means for controlling the armature by the 55 presence and absence of current in the stator winding, and a contact controlled by the armature.

8. In combination, a signal biased to one 60 position of indication, means for moving it to another position; and an inductive device for holding the signal in the latter position comprising a stator, a rotor, an energizing winding for the stator, a tractive armature controlled by the stator, and a contact controlled by the armature. 65

9. In combination, a signal biased to one position of indication, means for moving it to another position; and an inductive device for holding the signal in the latter position comprising a stator, a rotor, an energizing 70 winding for the stator, a slot in the stator, a tractive armature bridging the gap formed by the slot, means for causing part of the magnetic flux in the rotor to pass through the tractive armature and a contact controlled by the said tractive armature. 75

10. In combination, a signal biased to one position of indication, means for moving it to another position; and an inductive device for holding the signal in the latter 80 position comprising a stator, a rotor, an energizing winding for the stator, a slot in the stator between two adjacent poles thereof, a tractive armature arranged to bridge the gap formed by the slot, means for causing 85 the magnetic flux from the two said adjacent poles to pass through the tractive armature instead of returning through the stator, and a contact controlled by the tractive armature. 90

11. In combination, a signal biased to one position of indication, means for moving it to another position; and an inductive device for holding the signal in the latter position comprising a stator, a rotor, an energizing 95 winding for the stator, a slot in the stator between two adjacent poles thereof, a tractive armature arranged to bridge the gap formed by the slot, an electric circuit on each of said adjacent poles each of which 100 circuits is so placed that its plane is parallel to the normal direction of magnetic flux in the pole, and a contact controlled by the tractive armature.

12. In combination, a signal biased to one position of indication, means for moving it to another position; an inductive device for holding the signal in the latter position comprising a stator, a rotor, an energizing winding for the stator, a slot in the stator between two adjacent poles thereof, a tractive armature arranged to bridge the gap 110 formed by the slot, an electric circuit on each of said adjacent poles each circuit comprising conductors extending through the pole and conductors connecting said conductors on both sides of the stator, each circuit being so placed that its plane is parallel to the normal direction of the magnetic flux in the pole, and a contact controlled by the tractive armature. 115

13. In combination, a signal biased to one position of indication, means for moving it to another position, and a holding device for holding the signal in the latter position comprising a stator, a squirrel-cage rotor, and a single phase winding for the stator. 125

14. In combination, a signal biased to one position of indication, means for moving it to another position; and a holding device 130

for holding the signal in the latter position comprising a member provided with poles and a squirrel-cage member one of which members is fixed and the other of which is 5 operatively connected with the signal, and an energizing winding for the member provided with poles.

In testimony whereof I affix my signature in presence of two witnesses.

JOHN D. TAYLOR.
